PIANO ACTION

Alton F. Dinsmore, Fairport, N. Y., assignor to
Aeolian American Corporation, East Rochester,
N. Y., a corporation of New York

Application February 24, 1938, Serial No. 192,284

5 Claims. (Cl. 84—240)

This invention relates to piano actions, and pertains more particularly to actions adapted for use in small upright pianos.

It is an object of the invention to provide an action in which the parts are so arranged as to be accommodated within a case which is relatively low in height and relatively shallow in depth.

It is a further object of the invention to provide an action of this type adapted for small pianos without sacrificing any of the capabilities of the usual upright piano action.

Other objects and advantages of the invention will appear hereinafter.

A preferred embodiment of the invention selected for purposes of illustration is shown in the accompanying drawing, in which:

Figure 1 is a vertical section through the action, all parts of the piano except those essential to the action being eliminated.

Figure 2 is a similar view of a modified form of the invention, the conventional parts of the hammer action and key being omitted.

Referring to the drawing, the action is illustrated in its normal relation to a string 1, plate 2 and sounding board 3 of the piano. A keybed 4 is also shown, supporting keys 5.

The hammer action illustrated is of standard construction for upright pianos and is supported on the usual hammer rail 6. It comprises the usual parts including the hammer 7, damper 8, damper lever 9, back check 10, jack 11, bridle strap 12 and wippen 13. The usual spring rail 14 and hammer rest rail 15 are also provided.

Mounted below the wippons 13 is a rail 16 having secured thereto upper and lower flanges 17 and 18 on which are pivotally mounted upper and lower arms 19 and 20. Pivotally connected to the ends of the arms 19 and 20 is a vertical member 21, the upper end of which engages the under side of the wippen 13. The member 21 is provided with a projecting portion 22 for connection with one end of a lifter wire 23, the other end of which extends through an aperture in the rear end of the key 5. If desired, the upper end of the wire 23 may be threaded to receive an adjusting nut 24.

As will be apparent, when the pianist depresses the front end of the key in the usual manner, the rear end rises, causing the wire 23 to lift arms 19 and 20 and the member 21 to swing the wippen about its pivot to operate the hammer. It will be observed that while the end of the member 21 which engages the wippen moves in an arc having a radius equal to the distance between the pivot points of arm 19, the center of

said arc lies above the fixed pivot point of arm 19 at a point close to the pivot of the wippen. Consequently the said arc nearly coincides with the arc of the wippen, and since under these conditions there is only slight relative movement between the upper end of the member 21 and the wippen, there is very little friction therebetween.

Another advantage of this construction is that since the parts 19, 20 and 21 are all located beneath the wippen, the case can be made very shallow in depth, thus enhancing the small and graceful appearance of the piano.

A modified form of the invention is illustrated in Figure 2. In this form, a single arm 25 is pivotally mounted on a flange 26 and the lifter 15 wire 23 is connected directly to the arm. Pivotally mounted in a slot 27 in the arm 25 is a vertical member 28 the upper end of which engages the under side of the wippen 13. Said vertical member is provided with an extension 29 which is guided in an aperture 30 of rail 31.

It will be understood that the invention may be variously modified and embodied within the scope of the subjoined claims.

I claim as my invention:

1. In an upright piano action including a hammer, wippen and key, in combination, an arm pivoted at a fixed point below the pivot of said wippen and extending forwardly beneath said wippen with the movable end of said arm below the movable end of said wippen, a vertical member pivoted to said arm and extending upwardly from said arm to contact said wippen, said arm, member and wippen being located below said key, means to guide said vertical member to hold it in vertical position, and means connected to said key and depending therefrom to operate said arm.

2. In an upright piano action including a hammer, wippen and key, in combination, an arm pivoted at a fixed point below the pivot of said wippen and extending forwardly beneath said wippen with the movable end of said arm below the movable end of said wippen, a member pivotally connected to said arm extending upwardly therefrom to contact said wippen, said arm, member and wippen being located below said key, and means connected to said key and depending therefrom to operate said arm.

3. In an upright piano action including a hammer, wippen and key, in combination, an arm pivoted at a fixed point below the pivot of said wippen and extending forwardly beneath said wippen with the movable end of said arm below the movable end of said wippen, a member pivotally

connected to said arm extending upwardly therefrom to contact said wippen, said arm, member and wippen being located below said key, and a lifting wire depending from said key and connecting said key and said member to transmit motion of said key to said member and said wippen.

4. In an upright piano action including a hammer, wippen and key, in combination, a pair of pivoted arms arranged one above the other and extending substantially parallel to said wippen, a vertical member pivoted to said horizontal arms and contacting said wippen, said arm, member and wippen being located below said key, and means connected to said key and depending

therefrom to lift said horizontal arms and vertical member to thereby operate said wippen.

5. In an upright piano action including a hammer, wippen and key, in combination, a pair of pivoted arms arranged one above the other and extending substantially parallel to said wippen, a vertical member pivoted to said horizontal arms and contacting said wippen, said arm, member and wippen being located below said key, and a lifting wire depending from said key and connected to said vertical member to transmit motion of said key to said vertical member and said wippen.

ALTON F. DINSMORE.
